UNITED STATES PATENT OFFICE

HAROLD MASON, OF HYDE, ENGLAND, ASSIGNOR TO SPENCER & COOK, LIMITED, OF STALYBRIDGE, ENGLAND

MEANS FOR TURNING SHEETS OF PAPER AND THE LIKE IN FOLDING, RULING, AND OTHER MACHINES

Application filed June 16, 1930, Serial No. 461,288, and in Great Britain July 8, 1929.

This invention has reference to means for turning sheets of paper or the like in machines for folding, ruling or otherwise operating upon such sheets, of the kind in which 5 the folding, ruling or other devices are arranged parallel to one another and means are provided between pairs of the devices for turning the sheet or the like through an angle so that the fold, ruling or other operation 10 given or performed by the second device is at an angle to the preceding fold, ruling or other operation.

The invention has for its object to provide an improved means for effecting the turning 15 of the sheets or the like in machines of the kind referred to.

A turning means in accordance with the invention comprises a gripper adapted to receive and grip a sheet or the like after same 20 has issued from the first of a pair of folding, ruling or other devices, and to be then rotated through a right or other suitable angle to turn the sheet and then release the sheet or the like which continues its travel to the 25 second device while the gripper returns to its original position.

In the accompanying drawings Fig. 1 is a longitudinal section, Fig. 2 is a plan and Fig. 3 is a fragmentary end view of one 30 form of sheet-turning means in accordance with the invention arranged between two sets of parallel folding devices.

Referring to the drawings, X and Y indicate, respectively two folding devices arranged in suitably spaced parallel arrangement, and comprising as hitherto, rollers x , x^1 and y , y^1 and reciprocating vertical blades x^2 , y^2 .

Between the folding devices X, Y are arranged, as hitherto, endless travelling tapes 4 which receive the folded sheets as they issue from the first folding device X, and convey them to the second folding device Y.

The tapes 4 are mounted on rollers 5, 6 which are driven by gears 5^a, 6^a. The upper runs of the tapes pass over a table 7 and to ensure the travel of the sheets by the tapes there are associated with the latter balls 8 mounted in cages 9 adjustably mounted on bars 10, which are adjustably mounted above

the table 7, so that the balls 8 normally bear on the tapes and hold the sheets in contact therewith so that the sheets move with the tapes. Such an arrangement of balls for ensuring the travel of the sheets by the tapes 55 is well known in folding machines and does not here call for further description.

At a suitable point intermediate of the two folding devices X, Y there is provided a rotary gripper comprising normally separated upper and lower horizontally arranged disc jaws 11, 12, respectively. The lower jaw 12 is fixed on a tubular spindle 13 mounted in a bracket 14 secured to the table 7 through which latter the spindle 13 passes. The upper jaw 11 is secured on a spindle 15 mounted in the tubular spindle 13 of the lower jaw 12. The upper jaw 11 is acted upon by springs 16 (Fig. 1) carried by a fence or register 17 and adjustable as to tension by means of a screw 18. The upper jaw also carries a pin 19 (Figs. 2 and 3) which passes through a hole in the lower jaw 12 to form a rotary driving connection between the two jaws and to also position the upper jaw above the 75 lower jaw.

The lower end of the tubular spindle 13 has mounted on it a disc 20 with which engages a bowl 21 on one arm of a bell-crank lever 22 pivoted at 23 in the bracket 14. The other arm of the bell-crank lever 22 is connected with one end of a link 24, the other end of which is slotted to embrace a shaft 26 and carries a bowl 27 adapted to co-operate with a cam 28 on said shaft. 80

Integral with the disc 20 on the lower end of the tubular spindle 13 is a toothed wheel 29 with which gears a rack 30 slidably mounted in the bracket 14. The rack 30 is connected with one end of a link 31, the other end of which is slotted to embrace the shaft 26 and carries a bowl 32 adapted to co-operate with a cam 33 on the shaft which is driven from any suitable moving member of the machine. 85

In operation, a folded sheet issuing from the first folding device X is received by the tapes 4 and travelled thereby until its leading edge enters between the disc jaws 11, 12, as shown in dot-and-dash lines at 34, Fig. 2. The cam 28 on the shaft 26 by its engagement 90

with the bowl 27 then operates the link 24 to rock the bell-crank lever 22 which lifts the lower disc jaw 12 to grip the sheet. At this moment the link 31 is operated by the engagement of the cam 33 with the bowl 32, to slide the rack 30 to actuate the wheel 29 to turn the gripper and the sheet through 90° and with its former leading edge against the fence or register 17, as shown in dot-and-dash lines at 35 in Fig. 2. As soon as the sheet is turned the cams 28, 33 release the bowls 27, 32 and the parts of the gripper are returned to their initial positions by the springs 24^a, 31^a which have one of their ends connected with the links 24, 31, respectively, and their other ends anchored on the bracket 14. The turned sheet is then travelled by the tapes 4 to the second folding device Y by means of which it is folded in a direction at right angles to the fold made by the first folding device X.

It will be apparent that the operations of the cams 28, 33 must be appropriately timed relatively to the travel of the sheets as they issue from the first folding device X.

Although the invention has been exemplified in its application to the turning of sheets for folding operations, it will be manifest that the invention is equally applicable to the turning of sheets for ruling or other operations.

What I claim as my invention and desire to secure by Letters Patent is:—

- 35 1. In machines for folding, ruling or otherwise operating upon sheets of paper or the like, the combination with means for conveying a sheet from one to the other of a pair of folding, ruling or other devices, of a gripper adapted to receive and grip a sheet after same has issued from the first of said devices and to be then rotated to turn the sheet through a desired angle and to then release the sheet and return to its original position.
- 40 2. In a machine according to the preceding claim, a gripper comprising upper and lower jaws normally separated to receive the sheet, means for closing said jaws to grip the sheet, and means for rotating the jaws together to turn the sheet.
- 45 3. In a machine according to claim 1, a gripper comprising a lower disc jaw carried by a tubular spindle, an upper jaw carried by a spindle mounted in said tubular spindle, a rotary driving connection between said jaws, a means for raising said lower jaw relatively to said upper jaw, and means for rotating the said lower jaw.

In witness whereof I have hereunto set my hand.

HAROLD MASON.
